OF D 17,442

DESIGN.

—o—
H. HUNT.

CARPET.

No. 17,442.

Patented July 12, 1887.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of **Design No. 17,442, dated July 12, 1887.**

Application filed June 18, 1887. Serial No. 241,804. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists, mainly, of escutcheon-shaped figures of broken outline surrounded with a fantastic scroll-work of leaves and stems bearing circular flowers. The leaves are long and slender and of very irregular outline and curve around the large figures. 15 20

What I claim as new, and desire to secure by Letters Patent, is—

The design for carpets, consisting of the design substantially as shown.

HENRY HUNT.
